Primary Examiner — Mitchell Siegel(74) *Attorney, Agent, or Firm* — Workman Nydegger(57) **CLAIM**

The ornamental design for a ball launcher, as shown and described.

DESCRIPTION

FIG. 1 is a perspective view of a ball launcher according to the present invention;

FIG. 2 is a front view of the ball launcher of FIG. 1;

FIG. 3 is a back view of the ball launcher of FIG. 1;

FIG. 4 is a first side view of the ball launcher of FIG. 1; FIG. 5 is a second, opposite side view of the ball launcher of FIG. 1;

FIG. 6 is a top view of the ball launcher of FIG. 1; and, FIG. 7 is a bottom view of the ball launcher of FIG. 1.

The broken lines shown are directed to environmental structure and are for illustrative purposes only. The broken lines form no part of the claimed design.
